CLAIM

We claim the ornamental design for a baseball shaped transparency viewer, as shown and described.

DESCRIPTION

FIG. 1 is a front perspective viewer showing the baseball shaped transparency view of our new design;

FIG. 2 is a rear perspective view thereof;

FIG. 3 is a front view thereof;

FIG. 4 is a rear view thereof;

FIG. 5 is a side view, the opposite side view being a mirror image thereof; and,

FIG. 6 is a top view of the baseball shaped transparency viewer, the bottom view being identical, of our new design.
